US0D1010316S

(12) **United States Design Patent** (10) Patent No.: **US D1,010,316 S**
(45) Date of Patent: ** Jan. 9, 2024

(54) **BAG**

(71) Applicant: **DELVAUX CREATEUR SA**, Brussels (BE)

(72) Inventor: **Marc Valeanu**, Brussels (BE)

(**) Term: **15 Years**

(21) Appl. No.: **35/515,057**

(22) Filed: **Aug. 16, 2022**

(80) **Hague Agreement Data**

Int. Filing Date: **Aug. 16, 2022**

Int. Reg. No.: **DM/222965**

Int. Reg. Date: **Aug. 16, 2022**

Int. Reg. Pub. Date: **Sep. 2, 2022**

(30) **Foreign Application Priority Data**

Feb. 24, 2022 (WO) WIPO114036

Primary Examiner — Jennifer L Watkins

Assistant Examiner — Samantha Lynne Brodowski

(57) **CLAIM**

The ornamental design for a bag, as shown and described.

DESCRIPTION

1.1 is a front perspective view of a bag, showing my new design;

1.2 is a front view thereof;

1.3 is a back view thereof;

1.4 is a right-side view thereof;

1.5 is a left-side view thereof;

1.6 is a top view thereof;

1.7 is a bottom view thereof;

In the representations of the design the pale grey portions are not claimed.

1 Claim, 7 Drawing Sheets
